(57) **CLAIM**

The ornamental design for a handheld scale with decorative design, as shown and described.

DESCRIPTION

FIG. 1 is a top-side perspective view of my new handheld scale with decorative design

FIG. 2 is a top plan view of my new handheld scale with decorative design

FIG. 3. is a bottom plan view of my new handheld scale with decorative design

FIG. 4 is a left side elevational view of my new handheld scale with decorative design

FIG. 5 is a rear elevational view of my new handheld scale with decorative design

FIG. 6 is a front elevational view of my new handheld scale with decorative design

FIG. 7 is a top-side perspective view of my new handheld scale with decorative design without the removable cover; and,

FIG. 8 is a top plan view of my new handheld scale with decorative design without the removable cover.

My handheld scale with decorative design is characterized by a decorative case that looks similar to a cellular telephone with a removable cover. When the cover is removed, a rectangular-shaped weighing table is revealed with a square-shaped LCD display with touch-screen functional buttons.
